UNITED STATES PATENT OFFICE

CHARLES W. FRANK, OF ELIZABETH, NEW JERSEY

CHECK NOZZLE

Application filed September 15, 1928. Serial No. 306,145.

This invention relates to an improved type of nozzle, designed particularly for use upon gasoline dispensing hose, the primary object of the invention being to provide a nozzle having associated therewith a check valve which, when the nozzle is directed downwardly, as for example when being inserted into a filling opening of a tank, opens to discharge gasoline and when returned to the usual up-

bodying the present invention associated therewith;

Fig. 2 is a longitudinal sectional view of the discharge end of the nozzle, and through the valve, showing the valve in closed position; and

Fig. 3 is a sectional view on the line 3—3 of Fig. 1, the valve being shown in elevation.

Referring to the drawing in detail, numeral 1 indicates generally a hose nozzle of the

described having a discharge end provided with an interior valve seat, a valve head formed with an undercut portion to position upon said seat, a split skirt carried by the 5 valve head and extending into the nozzle, means carried by the nozzle for engaging and limiting the outward movement of the valve therefrom, said valve head when seated completely covering the discharge end of the 10 nozzle.

2. A dispensing nozzle of the character described comprising a tubular body having the inner edge of one end beveled to provide a valve seat, a valve head of substantially 15 the same overall diameter as the body and having a beveled underface adapted to position upon said seat, a pair of members extending from the inner face of said valve head and at diametrically opposite points there- 20 on and further having their outer faces curved to conform to the curvature of the nozzle wall, said spaced members being relatively snugly received in the nozzle and each having a longitudinally extending closed slot 25 formed therethrough, and a retaining pin ex- tended transversely of the nozzle through the slots of said members for limiting the out- ward movement of the valve head, said head being permitted to extend a substantial dis- 30 tance beyond the nozzle.

In testimony whereof I hereunto affix my signature.

CHARLES W. FRANK.
